UNITED STATES PATENT OFFICE.

CHARLES B. KING AND CLARENCE B. WESTON, OF MARION, OHIO, ASSIGNEES TO THE MARION STEAM SHOVEL COMPANY, OF MARION, OHIO, A CORPORATION OF OHIO.

EXHAUST-NOZZLE.

1,154,026.

Specification of Letters Patent. Patented Sept. 21, 1915.

Application filed October 25, 1913. Serial No. 797,239.

To all whom it may concern:

Be it known that we, CHARLES B. KING and CLARENCE B. WESTON, citizens of the United States, residing at Marion, in the 5 county of Marion and State of Ohio, have invented certain new and useful Improvements in Exhaust-Nozzles, of which the following is a specification, reference being had therein to the accompanying drawing.

10 This invention relates to a device for producing a forced draft through the flues of a boiler and is designed more particularly for use in connection with vertical boilers of portable engines which necessarily employ

15 a short stack.

It has been customary heretofore to discharge exhaust steam from the engine into the stack at the base thereof for the purpose of creating a forced draft through the 20 stack in a well-known manner. The stack of the ordinary portable boiler is so short, however, that the steam would pass from the discharge end of the exhaust pipe through the center of the stack and escape 25 from the top thereof before it had spread out sufficiently to completely fill the stack. As a result the suction created thereby is very materially reduced. Further, it has been found that in boilers of the type under 30 discussion there is a strong tendency for the draft to pass upward through the central flues of the boiler to the exclusion of the outer flues, thus tending to overheat the central flues while the outer flues remain 35 cool.

The object of the present invention is, first, to provide means whereby the exhaust may be discharged into the short stack of a portable engine or the like in a manner to 40 create a maximum of suction in the stack and through the flues of the boiler; second, to provide means for causing a substantially equal distribution of the draft among the several flues; and third, to provide means 45 whereby the exhaust steam may be utilized to prevent the distributing device from being overheated and distorted by the heat within the boiler.

In the accompanying drawings, Figure 1 50 is a vertical, sectional view taken centrally through a vertical boiler of the submerged flue type showing the exhaust nozzle and deflector; and Fig. 2 is a detail view of the combined exhaust nozzle and deflector.

In these drawings we have illustrated the 55 invention as applied to a boiler of the submerged flue type in which the upper ends of the flues are below the water level and are connected with the stack by means of a conical housing or uptake but it is not to 60 be understood that the invention is necessarily limited to this type of engine.

In carrying out the invention we place the exhaust nozzle within the boiler at a point remote from the lower end of the stack. 65 Consequently, the steam discharged from the nozzle will have an opportunity to spread before it reaches the stack and when it does reach the stack will completely fill the same so that the upward movement of 70 the steam will create a strong suction within the flues in the boiler. We have further provided a distributor or deflector which is arranged above the central flues of the boiler and so mounted with relation to the 75 stack that the suction will act with substantially equal force on all the flues, and further we have combined the deflector with the exhaust nozzle in such a manner that the 80 exhaust steam will act constantly upon the 80 deflector and prevent the same from being overheated. As a result of this organization we secure a maximum of draft and distribute this draft substantially equally among the several flues of the boiler. 85

As illustrated in the drawings the boiler is indicated at 1, having a fire box in the lower portion thereof and vertical flues 3 immediately above the fire box. These flues terminate below the normal water line of the 90 boiler and extending upwardly from the upper ends of the flues is a conical housing 4, sometimes known as an "uptake," which terminates at the base of and communicates with the smoke stack 5. Extending into the 95 upper end of the casing 4 is an exhaust pipe 6 of the engine, which is not here shown and this pipe extends downward to a point remote from the lower end of the stack and in the present instance more than half the distance between the base of the stack and the tops of the flues. Secured to the lower end 100 of the exhaust pipe 6 is a discharge nozzle 7 which constitutes the discharge end of the pipe and is in the form of a casing closed at 105 its bottom and side walls and having two openings in its top wall, one to receive the exhaust pipe and the other to constitute the

discharge opening of the nozzle, as indicated at 8. The exhaust steam entering the closed casing of the nozzle is deflected upward and discharged from the opening 8 at a point considerably below the base of the stack. As a result the steam will spread as it passes upward and by the time it has reached the base of the stack will have spread out to such an extent that it will completely fill the stack, 10 thus creating a powerful suction as it sweeps upward through the stack. This suction acts upon the flues to create a forced draft through the same. The nozzle 7 may be supported in any suitable manner but in the 15 present instance in addition to its connection with the exhaust pipe it is provided with a supporting rod 9 which tends to hold the same in its proper position. We have also mounted within the casing 4 above the flues 20 a deflector and in the present instance this deflector is formed integral with and forms a part of the discharge nozzle. To this end the lower portion of the discharge nozzle is in the form of an inverted cone, as shown at 25 10, and the apex of this cone is arranged substantially centrally of the group of flues 4. This deflector is interposed directly between the stack and the flues and prevents the suction through the stack from acting directly 30 on the central flues. The suction created by the passage of the exhaust through the stack acts upon the annular space between the combined nozzle and deflector and the wall of the casing or uptake 4 and, consequently, 35 the outer flues are affected thereby to an extent substantially equal with the inner flues. By combining the deflector or distributor 10 with the nozzle 7 the steam passing through the nozzle acts on the deflector and prevents 40 the same from being overheated, to the point of destruction, by the intense heat from the flues.

The operation of the device will be readily understood from the foregoing description 45 and it will be apparent that we have so arranged the discharge nozzle for the exhaust steam that the discharge of the steam into the stack will produce a maximum suction through the flues; further, that we have distributed this suction so that it will act on all 50 the flues with substantially equal force and no one flue or group of flues will be overheated while others are underheated; and further, that we have so constructed and arranged the distributing device or deflector 55 that it will not be destroyed by the heat in the flues.

While we have shown and described one 60 embodiment of our invention it will be understood that this has been chosen for the purposes of illustration only and that we do not desire to be limited to the details of construction shown and described, for obvious modifications will occur to a person skilled 65 in the art.

Having thus fully described our invention, what we claim as new and desire to secure by Letters Patent, is:—

1. The combination, with a boiler having vertical flues, a stack arranged above said flues and spaced away therefrom, and an uptake arranged within said boiler and connecting said flues with said stack, of an exhaust pipe leading into said uptake and discharging into said stack, the discharge 75 end of said pipe being arranged between the base of the stack and the flues at a point remote from the base of the stack and substantially centrally of the flues, and a deflector arranged in alinement with the discharge end of said exhaust pipe between the same and said flues to deflect the products of combustion toward the walls of said uptake on all sides of said deflector and equalize the draft through the several flues. 85

2. The combination, with a boiler having vertical flues, a stack supported by said boiler above said flues and in substantial alinement therewith, and a housing within said boiler connecting said flues with said stack, of a deflector arranged within said housing near said flues and in alinement with the base of said stack to direct the products of combustion toward the wall of said housing on all sides of said deflector and cause the draft through said stack to be distributed substantially equally to the several flues. 95

3. The combination, with a boiler having flues, a stack supported above said flues, and a housing connecting said flues with said stack, of a combined nozzle and deflector supported within said housing below said stack and directed toward the stack, and an exhaust pipe communicating with said nozzle. 100

4. The combination, with a boiler having flues, a stack supported above said flues, and a housing connecting said flues with said stack, of an exhaust pipe extending into said boiler at the upper end thereof and having a portion extending downward into said housing, a nozzle carried by said downwardly extending portion of said exhaust pipe and having its discharge opening 110 directed toward said stack. 115

5. The combination, with a boiler having vertical flues, and a stack supported by said boiler above said flues, of a hollow deflector interposed between said stack and said flues, and means for causing steam to circulate in 120 said deflector.

6. The combination, with a boiler having vertical flues, a stack supported by said boiler above said flues, and a housing within said boiler connecting said flues with said stack, of a hollow deflector arranged within said housing and interposed between said stack and said flues, and means for introducing 125 steam into said deflector. 130

7. The combination, with a boiler having vertical flues, a stack supported by said boiler above said flues, and a housing within said boiler connecting said flues with said stack, 5 of a discharge nozzle supported within said housing between the base of said stack and said flues, directed toward said stack and having a lower portion shaped to form a deflector, and an exhaust pipe connected 10 with said nozzle.

8. The combination, with a boiler having flues, and a stack spaced away from said flues, of a discharge nozzle interposed between said stack and said flues and having a 15 portion forming a deflector, and an exhaust pipe connected with said nozzle.

9. The combination, with a boiler having flues, and a stack spaced away from said flues, of a discharge nozzle interposed between said stack and said flues and having a 20

portion in the form of an inverted cone arranged in alinement with said flues and having its apex arranged centrally of said flues, and a steam pipe connected with said nozzle.

10. The combination, with a boiler having flues, and a stack supported above said flues, of a combined nozzle and deflector supported between said stack and said flues in substantial alinement with said flues and having its discharge opening directed to 25 30 toward said stack, and an exhaust pipe communicating with said nozzle.

In testimony whereof, we affix our signatures in presence of two witnesses.

CHARLES B. KING.
CLARENCE B. WESTON.
